FLUSH TANK

Filed March 24, 1925

FIG. 1

Inventor

S. H. Smith

By Watson E. Coleman
Attorney

UNITED STATES PATENT OFFICE

SAMUEL HERBERT SMITH, OF ATLANTIC CITY, NEW JERSEY, ASSIGNOR OF ONE-HALF
TO WILLIAM B. LOUDENSLAGER, OF ATLANTIC CITY, NEW JERSEY

FLUSH TANK

Application filed March 24, 1925. Serial No. 18,003.

This invention relates to certain improvements in flush tanks and has relation more particularly to a device of this general character employing an overflow pipe together with a float and arm, and it is an object of the invention to provide means for limiting the downward movement of the float, said means being preferably engaged with or supported by the overflow pipe.

Another object of the invention is to provide in connection with a flush tank in which operates a hollow float or buoyant body provided with an opening in its lower wall, means for limiting the downward movement of said float or body so that when the water within the tank is discharged, the water within the float or body may readily drain out.

The invention consists in the details of construction and in the combination and arrangement of the several parts of my improved flush tank whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view partly in section and partly in elevation illustrating a flush tank constructed in accordance with an embodiment of my invention;

Figure 2 is a view in perspective of the stop member as herein disclosed unapplied.

As disclosed in the accompanying drawings, T denotes a flush tank provided therein with a conventional overflow pipe 1 and a well-known type of valve 2 which automatically opens when the water level within the tank T has been lowered to a predetermined extent. The valve 2 is of a type wherein it is under control of a float or buoyant body F operatively engaged with the movable element of the valve by the rod or arm 3. The float or buoyant body F herein disclosed is of the general type disclosed in my patent No. 1,465,370, dated August 21, 1923, and wherein said

float or body is of a tubular type and provided at its lower portion with an opening defined by a depending sleeve or neck 4.

In Figure 2, I illustrate in detail a hook-like member M for limiting the downward movement of the arm 3 as the water within the tank T is discharged therefrom, said member comprising an elongated arm 5 provided at its upper end with a returned elongated bill 6 providing means whereby the member M may be effectively engaged with the upper portion of the wall of the discharge pipe 1 and effectively supported thereby with the arm 5 extending downwardly thereof. The opposite or lower end portion of the arm 5 is continued by an upwardly and outwardly directed arm 7, said arm 7 together with the lower end portion of the arm 5 providing a saddle in which works the float rod or arm 3. As herein disclosed, the arm 5 is of such a length as to limit the downward movement of the arm or rod 3 when the same is in substantially a horizontal position or the valve 2 in full open position. By this means, it is assured that as the level of the liquid within the tank goes below the sleeve or neck 4 the water or moisture within the float or body F will be given full opportunity to drain out therefrom and thereby assure the float or body F continuing to operate with a maximum of efficiency.

In Figure 2, it is to be noted that the lower or adjacent ends of the arms 5 and 7 are connected by an interposed portion 8 integrally formed therewith whereby the portion 8 provides the stop with which the arm or rod 3 directly contacts.

From the foregoing description it is thought to be obvious that a flush tank constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my

invention in practice except as hereinafter claimed.

I claim:—

1. In a flush tank, the combination of a float having an arm, an overflow pipe, and means supported by the overflow pipe for limiting the downward movement of the arm and float.
2. In a flush tank, the combination of a float having an arm, and an overflow pipe, means for limiting the downward movement of the float comprising an elongated arm provided with means engageable with the overflow pipe for supporting said arm in applied position, said arm being disposed downwardly of the overflow pipe, an upstanding arm carried by the lower portion of the second named arm, the arm of the float working between the two arms.
3. In a flush tank, the combination of a float having an arm, and a overflow pipe, means for limiting the downward movement of the float comprising an elongated arm provided with means engageable with the overflow pipe for supporting said arm in applied position, said arm being disposed downwardly of the overflow pipe, an upstanding arm carried by the lower portion of the second named arm, the arm of the float working between the two arms, the third named arm being upwardly and outwardly disposed with respect to the second named arm.
4. In a flush tank, the combination of a float having an arm, and an overflow pipe, means for limiting the downward movement of the float comprising an elongated arm provided with means engageable with the upper portion of the wall of the overflow pipe for supporting said arm in applied position, said arm being disposed downwardly of the overflow pipe, an upstanding arm carried by the lower portion of the second named arm, the arm of the float working between the two arms.
5. In a flush tank, the combination with a float ball having an arm, an overflow pipe and means secured to said overflow pipe for engaging said arm and limiting the downward movement of said ball.
6. In a flush tank, the combination of a float ball having an arm, an overflow pipe and means for limiting the downward movement of said ball, said means comprising a hook secured to said overflow pipe, said hook being adapted to engage the arm of said float ball.

In testimony whereof I hereunto affix my signature.

SAMUEL HERBERT SMITH.
